DESIGN FOR A PIN-UP LAMP

Thomas J. Smith, Seattle, Wash.

Application September 27, 1948, Serial No. 148,794

Term of patent 3½ years

(Cl. D48—4)

To all whom it may concern:

Be it known that I, Thomas J. Smith, a citizen of the United States, residing at Seattle, in the county of King and State of Washington, have invented a new, original, and ornamental Design for a Pin-Up Lamp, of which the following is a specification, reference being had to the accompanying drawing, forming part thereof.

Fig. 1 is a perspective view of a pin-up lamp showing my new design, as seen from above the level of the lamp.

Fig. 2 is a perspective view of the same, as seen from below the level of the lamp.

Fig. 3 is a side view of the lamp; and

Fig. 4 is a top view.

I claim:

The ornamental design for a pin-up lamp, as shown.

THOMAS J. SMITH.
